[57] ABSTRACT

A reed switch comprises a pair of reeds positioned so that the locus of operation of the free end of at least one of the reeds does not cross the other of the reeds. Contact material is provided in the area of the free end of each of the reeds. The contact material on at least one of the reeds is mounted to deviate from the free end of the one of the reeds.

REED SWITCH

The present invention relates to a reed switch. More particularly, the invention relates to a reed switch used to close and open an electric circuit.

The reed switch of the invention comprises a pair of reeds of ferromagnetic material positioned in a manner whereby the locus of operation of the free end of at least one of the reeds cannot cross the other reed. The reeds are sealed in a glass tube having an inert gas such as, for example, nitrogen, therein. The reed switch is positioned in a coil to provide a reed relay.

A defect of a known type of reed switch is that the material of the contacts and the method of manufacture of the contacts are extremely limited. The life of the reed switch is shortened due to this defect, because the contact gap cannot be made large enough and the thickness of the contacts cannot be made large except in a large-size switch.

Another defect of known types of reed switch is the very short sliding at the contact. Still another defect of known types of reed switch is that in order to protect the contact from adhesion by melting, a protective circuit is required, since the release is non-abrupt and has a weak initial or opening force. Another defect of known types of reed switch is that they cannot be utilized as a threshold limit element, because the working ampere-turns and the release ampere-turns are different.

The principal object of the invention is to provide a new and improved reed switch which overcomes the disadvantages of known types of reed switch.

An object of the invention is to provide a reed switch having a long life.

Another object of the invention is to provide a reed switch having long sliding at the contact.

Still another object of the invention is to provide a reed switch in which there is no danger of adhesion of the contacts and there is no protective circuit utilized to prevent such adhesion.

Another object of the invention is to provide a reed switch which may be utilized as a threshold limit element.

Another object of the invention is to provide a reed switch having a large contact gap, thick contacts and long sliding at the contacts, which reed switch is particularly suitable for use in telecommunication equipment, telephone exchange equipment and various electronic equipment and functions therein with long life, high reliability, efficiency and effectiveness.

Yet another object of the invention is to provide a reed switch having impulsive release of the contacts.

Another object of the invention is to provide a reed switch having the same working ampere-turns and releasing ampere-turns, so that it is utilizable as a reed relay and as a threshold limit element.

In accordance with the invention, a reed switch comprises a pair of reeds positioned so that the locus of operation of the free end of at least one of the reeds does not cross the other of the reeds. Contact material is provided in the area of the free end of each of the reeds. The contact material on at least one of the reeds is mounted to deviate from the free end of the one of the reeds.

The reeds comprise ferromagnetic material. The free ends of the reeds are spaced from each other in every condition of the switch and the contact material on the

one of the reeds extends beyond the free end of the one of the reeds toward the other of the reeds. The contact material on the one of the reeds comprises a spring.

The contact material on the one of the reeds may extend substantially linearly beyond the free end of the one of the reeds. The contact material on the one of the reeds may be bent away from the contact material on the other of the reeds but extends substantially linearly over the contact material on the other of the reeds.

10 The contact material may be integrally formed with the one of the reeds and may comprise a spring.

In order that the invention may be readily carried into effect, it will now be described with reference to the accompanying drawings, wherein:

15 FIG. 1 is a view, partly in section, of a reed switch of the prior art;

20 FIG. 2 is a perspective view of the contact area of a reed switch of the prior art;

25 FIG. 3 is a graphical presentation of the magnetic characteristics of a reed switch of the prior art;

30 FIG. 4 is a perspective view of the contact area of an embodiment of the reed switch of the invention;

35 FIG. 5a is a schematic diagram of the contact area of another embodiment of the reed switch of the invention;

40 FIG. 5b is a schematic diagram of the contact area of still another embodiment of the reed switch of the invention;

45 FIG. 6 is a graphical presentation of the magnetic characteristics of the reed switch of the invention;

50 FIG. 7 is a graphical presentation of the magnetic characteristics of reed switches of the prior art and the reed switch of the invention; and

55 FIGS. 8a, 8b, 8c, 8d and 8e are perspective views of different modifications of yet another embodiment of the reed switch of the invention.

60 FIG. 1 illustrates a known type of reed switch. In FIG. 1, reeds 1 and 2 are of rod-like configuration and comprise, for example, 52 alloy.

The free ends of the reeds 1 and 2, which are to bear the contact material, are melted down in order to provide them with an appropriate spring or resiliency characteristic. The free end 3 of the reed 1 is plated with the contact material. The free end 4 of the reed 2 is plated with the contact material. The contact material comprises precious metals.

65 The reeds 1 and 2 are sealed in a glass tube 5 in the area of their contacts 3 and 4 in order to prevent oxidation of said contacts. The reed switch may be inserted into a coil or winding 6 which may be wound on a bobbin 7, thereby providing a reed relay.

When the coil 6 is energized, the reeds 1 and 2 are magnetized and their contacts 3 and 4 move under the influence of the attractive magnetic force into contact with each other.

70 FIG. 2 illustrates the area of the contacts of a known type of reed switch. FIG. 2 is a representation of the contact area of the reed switch of FIG. 1 on a considerably enlarged scale. In FIG. 2, the area 8 is the melted down part of the reed 1 and the area 9 is the melted down part of the reed 2. The reed 1 has a contact part 11, which is the free end of said reed, plated with precious metals. The reed 2 has a contact part 12, which is the free end of said reed, plated with precious metals.

The contact areas 11 and 12 are positioned adjacent each other in a manner whereby the locus of operation of each crosses the other. The contacts 11 and 12 are spaced from each other by a distance x_1 . The force of magnetic attraction on the reeds 1 and 2 in their contact areas 11 and 12 is directly proportional to the gap or space x_1 . The space x_1 may thus not be increased since a large attractive force is required.

In a usual small-sized reed switch the distance x_1 is from 50 to 120 microns. For this reason, it is impossible to cover the contact areas 11 and 12 with thick non-magnetic material to provide bulk contacts. The contact areas are usually formed by thin non-magnetic material applied by plating or sputtering. The contact material is thus very restricted. Since the contacts 11 and 12 are thin, they suffer erosion, transfer and wear due to the impact of said contacts and the current flowing between said contacts at the instant of make and break after a specific number of operations. This results in bad contact or improper release. Furthermore, unevenness in the contacts due to the transfer is increased in accordance with the magnitude of the current flowing between said contacts.

Improper release may be caused by minute unevenness in a known reed relay in which the gap x_1 between the contacts cannot be made large. Furthermore, it is obvious that make and break of the large current which increases unevenness due to the transfer becomes impossible. In a conventional reed relay, the release is non-abrupt in the structure of FIG. 1, so that improper release is inevitable.

FIG. 3 illustrates the magnetic characteristic of a known reed switch. In FIG. 3, the abscissa represents the excitation in ampere-turns and the ordinate represents the magnetic flux density ϕ . As shown in FIG. 3, working ampere-turns are illustrated at a point m and the release ampere-turns are illustrated at a point n . The release ampere-turns are less than the working ampere-turns. This is due to the magnitude of the demagnetizing field. That is, the magnitude of the demagnetizing field is proportional to its length, provided that the material and cross-sectional area are the same.

When the contacts are released, the produced demagnetizing field is determined by the length of each reed, whereas when the contacts are closed or in contact, the produced demagnetizing field is determined by the sum of the length of each reed. Accordingly, the magnetic flux density effectively operating between the contacts is different when the contacts are released and when the contacts are closed. Thus, the point m of the working ampere-turns and the point n of the release ampere-turns are different. The conventional reed switch, in which the points m and n are different, thus cannot be utilized as the threshold limit element.

The defects and disadvantages of known reed switches are eliminated by the reed switch of the present invention. FIG. 4 shows a reed switch of the invention. In FIG. 4, the structure of the reed switch is the same as that of the known reed switch, except that the free ends of the reeds are spaced from each other and the free end of one of the reeds is extended in a direction toward the other. The free ends of a first reed 41 and a second reed 42 are spaced from each other by a distance or gap t . The free end of each of the reeds 41

and 42 thus does not come into contact with that of the other in any condition of the switch. The reeds 41 and 42 comprise magnetic material.

A contact 43 is provided in the area of the free end of the first reed 41. A contact 44 is provided in the area of the free end of the second reed 42. The contacts may be affixed to the corresponding reeds by any suitable means such as, for example, welding. The contact 44 of the reed 42 extends beyond the free end of said reed toward the reed 41. When the contacts 43 and 44 are closed or in contact due to a magnetic biasing field, the free ends of the reeds 41 and 42 are opposite each other and the magnetic force of attraction produced by the magnetic gradient is utilized as the contact force between said contacts. The reeds 41 and 42 comprise magnetic material such as, for example, 52 alloy. The contacts 43 and 44 comprise materials such as, for example, nickel, tungsten, molybdenum, lead, gold and silver, and palladium and mercury.

The thickness of the contact 44 is selected for suitable or appropriate stiffness so that said contact functions as a spring or resilient body. Since the free ends of the reeds 41 and 42 do not overlap, the gap x_2 between the contacts 43 and 44 thereof may be made large. The bottom surface of the reed 42 is spaced a distance x_3 from the bottom surface of the reed 41.

The reed switch of the present invention functions in the following manner. When the reeds 41 and 42 are magnetized by an exciting magnetic field, the contact 44 of the reed 42 abruptly approaches the contact 43 of the reed 41 and said contacts come into contact with each other. The movement of the contacts 43 and 44 in upward and downward directions is then stopped, but the reed 42 moves to decrease the distance x_3 . This causes the contact 44 to bend and produce the release force or the force against further movement of the reed 42.

The release force operates as the contact force between the contacts 43 and 44. The total release force is the sum of the release force based upon the displacement of the reeds 41 and 42 and the release force of the contact 44. Stabilization may be provided at the point where the total release force and the attractive force of the reeds 41 and 42 come to a balance. These are primarily the vertical components of such forces. The point of balance is a point at which the reeds 41 and 42 slip slightly up and down. That is, the balance is maintained under a magnetically biased condition.

After the contact 44 contacts the contact 43, the contact 44 is bent so that the contacts 44 and 43 slide in a linear distance shortened by the bending of the contact 44. Unevenness resulting from the transfer of the contacts 43 and 44 is scraped or removed by the sliding of said contacts and is accordingly flattened. This results in an improvement of improper release due to the transfer. Thus, the reed switch of the invention permits a greater make and break of the current than that of a conventional reed switch by making the contact gap x_2 the same as the contact gap x_1 of the conventional reed switch.

FIG. 6 illustrates the magnetic characteristic of the reed switch of the invention. In FIG. 6, the abscissa represents the excitation in ampere-turns and the ordinate represents the magnetic flux density ϕ . A point P in FIG. 6 represents the working ampere-turns and the

releasing ampere-turns, which are equal to each other. The working and releasing ampere-turns are equal, because of the difference of the reed switch of the invention over a conventional reed switch, which difference is that there is no contact between the reeds opposite each other and the magnitude of demagnetization is constant independent of the release and closing of the contact. Accordingly, the reed switch of the invention may be utilized as a threshold limit element, thereby expanding the utilization of the reed switch.

The speed of release of the contacts 43 and 44 of the reed switch of FIG. 4, after the release of the bent contact 44, is great compared to the speed of release of the contacts of a conventional reed switch, as shown in FIG. 2, for example. This is due to the addition of the release energy of the contact member 44 in the reed switch of FIG. 4. Thus, the reed switch of the invention provides impulsive release. Since the reed switch of the invention provides impulsive release, the force of contact and the force of release between the contacts are great, so that adhesion or sticking of the contacts is eliminated.

FIG. 7 illustrates the attractive force characteristics and explains the contact gap. In FIG. 7, the abscissa represents the displacement of the reed in millimeters and the ordinate represents the attractive force in grams. In the conventional reed switch of FIG. 2, x_1 is the displacement of the reeds 1 and 2. In the reed switch of the invention, as shown in FIG. 4, the reeds 41 and 42 are displaced by the distance x_3 . The distance x_3 is substantially vertical, extending up and down.

In FIG. 7, a curve 71 shows the attractive force characteristic of the conventional reed switch. A curve 72 shows the attractive force characteristic of the reed switch of the invention. In both cases, the reeds comprise a square bar of 52 alloy having a cross-sectional area of 0.37 mm². The thickness of the bar was 0.54 mm and the width of the bar was 0.82 mm. The gap t in the reed switch of the invention, as shown in FIG. 4, was 0.01 mm.

A curve 711 of FIG. 7 shows the release force characteristic of the conventional reed switch. A curve 721 shows the release force characteristic of the reed switch of the invention. The release force must always be less than the attractive force characteristic. If the release force is 5 grams, the release force of the conventional reed switch is under the tangent of the attractive force characteristic curve 71 from the point of 5 grams attractive force. If the attractive force characteristic 71 is selected in anticipation of a small surplus, the gap x_1 between the reeds 1 and 2 is approximately 0.15 mm.

In accordance with the invention, however, the release force characteristic shown by the curve 721 of FIG. 7 may be selected toward the same release force of 5 grams, in which case the displacement x_3 between the reeds 41 and 42 (FIG. 4) is approximately 0.34 mm. As hereinbefore described, the displacement of the reed switch of the invention is more than double the displacement of the conventional reed switch, so that the contact gap is greatly improved.

FIGS. 5a and 5b show another embodiment of the reed switch of the invention. In each of FIGS. 5a and 5b, the reeds 51 and 52 comprise magnetic material

such as, for example, 52 alloy. In each of FIGS. 5a and 5b, a contact 53 or 53' is affixed to the reed 51 and a spring 54 or 54' extends from the reed 52 toward the reed 51. A contact 55 or 55' is affixed to the spring 54 or 54' in each of FIGS. 5a and 5b.

In the embodiment of FIG. 5a, the contacts 53 and 55 are thin and there is a sufficient contact gap between them. The contact gap may, however, become insufficient due to the necessity for using thick contacts under the particular circumstances which determine the use of the reed switch. Thus, for example, the thick contacts 53' and 55' of FIG. 5b may be utilized. In such a case, the desired contact gap may be provided by bending the spring 54' away from the contact 53' but extending said spring substantially linearly over the contact 53'. The reed switch of the invention thus remedies poor contact or improper release created by contact members of a conventional reed switch which are not of the proper thickness.

FIGS. 8a to 8e are modifications of still another embodiment of the reed switch of the invention. FIG. 8b is a side view of the embodiment of FIG. 8a. In each of FIGS. 8a to 8e, a first reed 801 or 801' and a second reed 802 or 802' are provided in a sealed glass housing 803.

In FIGS. 8a and 8b, the reeds 801 and 802 are rods of magnetic material such as, for example, 52 alloy. The area of the free end of the reed 802 is pressed to provide a substantially plate-like portion 804. A substantially spherical contact 805 is affixed to the first reed 801 by any suitable means such as, for example, welding.

A contact 806 is affixed to the substantially flat portion 804 of the second reed 802 at an end 807 thereof. The contact 806 is resilient and functions as a spring. The contact 806 comprises a precious metal, such as, for example, tungsten, nickel, molybdenum, gold and silver, gold and lead, palladium, silver and palladium, and copper and palladium. The contact 805 comprises a precious metal of the same group of metals as the contact 806.

In the embodiment of FIG. 8c, the first reed 801 comprises a tube having an axial bore extending therethrough, instead of a rod, as in the embodiments of FIGS. 8a and 8b. The first reed 801 of FIG. 8c may thus be utilized for replacing inert gas of nitrogen and hydrogen, or reducing gas such as hydrogen and carbon monoxide, for the air in the glass housing 803 after said housing is sealed. That is, an inert or reducing gas is supplied through the axial bore of the reed 801. After the gas exchange is completed, the bore of the reed 801 is sealed by any suitable means such as, for example, welding.

In the embodiments of FIGS. 8d and 8e, the first and second reeds 801' and 802' have the configuration of plates. In each of FIGS. 8d and 8e, the first and second reeds comprise 52 alloy. The free end of the second reed 802' extends for an additional portion 808 in the embodiment of FIG. 8d. The additional portion 808 extends toward the first reed 801' and also extends substantially linearly over a contact 809 on said first reed. The extended contact portion 808 is resilient and functions as a spring. The contact 809 on the first reed 801' is affixed to said reed by any suitable means such as, for example, welding, and may have a cylindrical configuration.

In the embodiments of FIGS. 8d and 8e, the contact part 808 or 808' extending from the free end of the second reed 802' is integrally formed with said second reed. This eliminates the need for affixing a contact to the second reed and simplifies the manufacturing process. Furthermore, the contact area 808 or 808' is thin. The attractive force is produced at the contact part 808 or 808' and the contact force may be strengthened.

The difference between the embodiments of FIGS. 8d and 8e is that in FIG. 8d, a slot 811 is provided in the free end of the contact area 808' to form twin contact parts 812 and 813. This results in more reliable contact between the contact area 808' and the contact 809. More particularly, one of the contact parts 812 and 813 such as, for example, the contact part 813, has an oxide film. Furthermore, if there is a projection at the contact 809 which contacts the oxide film, the contact part 813 is bent. In this case, the other contact part 812 contacts the contact 809 and results in reliable contact and switching.

Although the embodiments of the invention have been described with reference to reed switches, the magnetic attraction structure of the invention is applicable to general electromagnetic switches. Furthermore, the aforescribed embodiments relate to a reed switch having a make contact. The invention, however, is applicable to a reed switch having a break contact by means of a simple well known technique.

While the invention has been described by means of specific examples and in specific embodiments, it should not be limited thereto, for obvious modifications will occur to those skilled in the art without departing from the spirit and scope of the invention.

We claim:

1. A reed switch comprising a pair of reeds of ferromagnetic material, at least one of said reeds being movable, said reeds having free ends spaced from one

another in every condition of the switch, a first contact member secured to one of said reeds and passing beyond the free end if said one reed to extend over the free end of the other reed, and a second contact member secured to said other reed, said switch being opened and closed at said contact members by the displacement of at least one of said reeds.

2. A reed switch as claimed in claim 1 wherein said first contact member comprises a spring.

3. A reed switch as claimed in claim 2 wherein said spring is flexed when said contact members are closed during operation of the switch.

4. A reed switch as claimed in claim 1 wherein said first contact member comprises a resilient plate-like

15 member having one end portion secured to said one reed, said resilient plate-like member normally being disposed in a fixed position relative to said one reed except when said contact members are mated during operation of the switch, whereupon said resilient plate-like member is flexed by virtue of the mating contact to apply a resilient force between said contact members, said resilient force being derived from the resiliency of said plate-like member.

5. A reed switch as claimed in claim 1 wherein said 25 second contact member is secured to said other reed at a position displaced from the free end of said other reed.

6. A reed switch as claimed in claim 1 wherein said first contact member extends substantially linearly beyond the free end of said one reed.

30 7. A reed switch as claimed in claim 6 wherein said first contact member is a flat plate.

8. A reed switch as claimed in claim 1 wherein said first contact member is bent away from said second contact member but extends substantially linearly over said second contact member.

35 9. A reed switch as claimed in claim 1 wherein at least one of said reeds comprises a hollow tube.
